United States Patent Office.

ANDREW J. STEVENS, OF SAN FRANCISCO, CALIFORNIA.

Letters Patent No. 100,814, dated March 15, 1870; antedated March 5, 1870.

IMPROVEMENT IN STEAM-ENGINE SLIDE-VALVES.

The Schedule referred to in these Letters Patent and making part of the same.

To all whom it may concern:

Be it known that I, ANDREW J. STEVENS, of the city and county of San Francisco, and State of California, have invented certain new Improvements in my so-called "Anti-Compression and Balanced Slide-Valve;" and I do hereby declare that the following is a full, clear, and exact description of the same, reference being had to the accompanying drawings and letters of reference marked theron, making a part of this specification, in which—

Figure 1 is a side view,

Figure 2 is a cross-section,

Figure 3 is an under-side view, and

Figure 4 is a plan or top view of the valve.

This invention consists in certain additional improvements in the construction and operation of my anti-compression and balanced slide-valve, for which Letters Patent were granted to me, bearing date June 18, 1862, and for improvements thereon July 7, 1863.

The additional improvements I now make are designed to render the valve of simpler and cheaper construction, and more effective in operation.

The valve is designed—

First, to release the steam, which may be in the cylinder on the exhaust side, after the exhaust-port has been closed by the inside lap on the valve, thereby preventing compression by the advancing piston.

Second, to relieve the pressure occurring when the piston is suddenly driven against the air or water, which may be in the cylinder.

Third, to partially protect the valve from the pressure of steam on its back, thus to relieve it from excessive friction on its face, and permit it to be moved with small expenditure of power.

To enable others skilled in the art to make and use my invention I will proceed to describe it as follows:

The main principles of my valve have been described in the previous Letters Patent granted to me, but to make my description of the improved parts clearly understood, I will here describe the valve complete, and afterward designate what is new and improved.

My valve is in part constructed like the common slide-valve, having same relations to the cylinder ports and steam-chest, and is operated by similar mechanism, but is further provided as follows:

To release the steam remaining in the cylinder when the main port is closed on the exhaust side, I provide steam passage-ways A A' leading from the face of the valve, midway between the exhaust-cavity and the edge, to the back of the valve, where they will open into the compartments B B' in the anti-compression steam-chamber C. (See fig. 2.)

Within these compartments B B' are provided the flat valves D D', which alternately open and close a communication with the central passage-way E, which

may either lead to the main exhaust, as shown in dotted lines, fig. 2, or directly to the atmosphere, as shown in same figure.

The valves D D' are held apart by the stems F F', which are a trifle longer than the distance between the seats of the valves they divide; thus, when one valve is driven to, the opposite valve will be pushed from its seat, and one or other of the steam-passages will be always open.

The anti-compression valve-chamber C is secured to the back of the main valve by the bolts G G', as shown in figs. 2 and 4.

The stems F F' are not solid with the valves, but set loosely between them, and are inserted in their positions through holes drilled in the side of the chamber in which they set, which holes are afterward plugged up by the plugs H H'.

The action of this part of my valve is as follows:

When, during the operation of the engine, the main exhaust-passage is closed, and the steam in the cylinder on the exhausting side has not all escaped, compression of the remaining steam, by the advancing piston is avoided, by reason of the expanding steam on the "steam side" closing its own anti-compression valve, and opening the one corresponding to the exhausting side, thus a free exit is provided for the unexhausted steam through the auxiliary exhausting passages, which connect the main ports in the cylinder with either the exhaust-port or the atmosphere.

The next part of my invention is the provision made for preventing a pressure which would be caused by the piston suddenly striking air or water, which might be in the cylinder.

This is accomplished by what I call the relief valves I I' in connection with the steam-passages K K'. These steam-passages K K' are simply branches from the anti-compression passages A A'. They are made to lead to the back of the main valve and into the steam-space.

The valves I I', which open and close these steam-passages K K', are confined in the cages L L', which are cast on the follower M. They are kept to their seats by the pressure of the steam in the steam-chest.

There may be holes l drilled through the tops of these cages, to insure the steam getting at the valve, if from any cause steam should be prevented from getting underneath the cage.

The valves I I' are simply long flat pieces of metal, just wide enough to work easy in their cages L L'.

The operation of this part of my invention may be thus described:

Let it be supposed that the cylinder contains water, and the engine is set in motion. As the piston advances upon the water with sudden action, it would create a pressure greater than that due to the expand-

ing steam in the other end of the cylinder. Now, since the anti-compression valve is only kept open by this steam pressure in the opposite end of the cylinder, then it must be closed when an excessive pressure shall occur in opposition to it. This will often happen when the piston drives suddenly against the air or water which may be in the cylinder. At this time, my relief-valve will come into use, for this excessive pressure, when greater than the steam pressure which keeps the valve seated, will raise it up from its seat, open the passage-way, and permit the air or water to escape into the steam-chest.

With this device, it will be seen that at no time can the pressure in the cylinder exceed that due to the actual steam pressure.

The last part of my invention is the arrangement for counterbalancing my valve, and inclosing a communication with the atmosphere for the escaping steam from the anti-compression chamber. This consists as follows:

On the top of the main valve, I provide the rim N, which extends around the valve inside of the relief-ports. It is of proportionate height and thickness of metal, as shown in drawing.

M is a follower, which slips over this rim N down to about a distance as shown in fig. 2.

The upper end of this follower terminates in a broad flange, P, which bears against the faced surface of the steam-chest cover.

I make the joint between the rim N and the follower M steam-tight, by casting in the angular groove or cavity, which extends around the top of the rim N, a ring, R, of soft expandible metal, as type metal. This ring R will be wedge-shaped, with its thin edge set upward, as shown in fig. 2. This ring may be cast with the follower in its place.

One or more elliptic springs S, having their ends inserted into cavities T in the follower M, and bearing in the center upon the back of the anti-compression valve-chamber, will serve to keep the follower against

the surface of the steam-chest cover, when no steam is in the steam-chest.

There will be two cages L L', as before described, cast on the follower, to inclose the relief-valves I I'.

This follower M operates to exclude the steam from the back of the valve, and thus protects the valve in a measure from the steam pressure, which would otherwise create a great amount of friction on the valve-face, which would cause a great expenditure of power in operating.

The steam acting against the base of the metal ring R will wedge it upward and outward tightly against the inside of the follower, and thus insure a steam-tight joint.

The pipe which leads from the top of the steam-chest cover may either lead to the main exhaust-pipe or elsewhere, as desired, or there need only be an opening left in the steam-chest cover.

The parts of this invention which are additional improvements on my previously-patented valve, and which I desire to have secured to me by Letters Patent of the United States, I will here designate and claim as of my invention as follows:

1. The improved anti-compression valves D D', being simply long flat pieces of iron or other metal, in combination with their valve-seats and the stems F F', for the purposes as set forth, and constructed in the manner substantially as described.

2. The relief-valves I I', in combination with their respective cages and steam-passages K K', for the purposes as set forth, and constructed and arranged in the manner substantially as described.

3. The wedge-shaped metal ring R, placed in the cavity around the top of the rim N, for the purposes as set forth, and constructed and arranged in the manner substantially as described.

ANDREW J. STEVENS.
